UNITED STATES PATENT OFFICE.

JOHN J. EAGAN, OF SAN FRANCISCO, CALIFORNIA.

CONCRETE VESSEL.

1,316,083.

Specification of Letters Patent. Patented Sept. 16, 1919.

Application filed July 11, 1918. Serial No. 244,401.

To all whom it may concern:

Be it known that I, JOHN J. EAGAN, a citizen of the United States, residing at the city of San Francisco, in the county of San Francisco and State of California, have invented certain new and useful Improvements 5 in Concrete Vessels, of which the following is a specification.

My invention relates to improvements in 10 concrete ships.

The object of my invention is to provide an improved construction of a concrete vessel having the great rigidity necessary to such type of vessel so as to withstand the 15 heaviest seas, and to carry out said object I construct a framework of hollow tubular members embedded in concrete and also fill said members with concrete, and also connect said concrete in the interior of said 20 members with the outer shell of concrete so as to form an integral and homogeneous mass of said material molded and reinforced with the metallic members therein.

My invention consists in the novel arrangement and combination of parts shown 25 in the accompanying drawing, described in the following specification and claimed in the appended claims.

Referring to the said drawing illustrating 30 my invention Figure 1 is a side view of a ship embodying my improved construction, parts thereof being broken away and shown in section. Fig. 2 is a transverse vertical section of the same.

In the figures A represents a concrete 35 vessel, having the reinforcement thereof made of tubular material to form the frame as shown. 2 is a central longitudinal tubular member running the length of the vessel 40 and forming a keel and the front end thereof is bent up as shown at 3 for forming the stem of the vessel and the rear end of said tubular member is also bent up as shown at 5. A curved member 4 is supported by 45 the tubular member 2 and its extension 5 is shown as a support for the stern of the vessel. The rudder 6 is connected to and supported by the bent portion 5 and the pivoted rod extends upwardly through the sleeve 50 encircling member 4, said sleeve being shown broken away in the drawing. Running transversely of the vessel at certain intervals and passing through the central tubular member at the bottom are ribs 9 and which 55 are bent up to form side supports for the vessel. Reinforcing and metallic tubes 10

are also placed at certain intervals between the members 9 running longitudinally for the purpose of forming a rigid structure the full length of the vessel, said ribs 9 being provided with central openings to receive said tubes therethrough. The hull of the vessel at the bottom is supported by tubular braces 11 running vertically from the lower portion 8 of ribs 9 and connected upwardly with transverse tubes 13 to support the upper wall 14 of the bottom and thereby with the surrounding concrete, as shown in section in the figures, forming compartments 12. At certain intervals and 60 spaced from each other are columns 15 mounted and coupled centrally through the vessel as shown to support the upper and lower decks 18, and the same are reinforced by means of transverse tubes 16 secured to 65 the said central columns and endwise to the opposite ribs 9. The decks and bottom have reinforcing tubes 17 running longitudinally the length of the vessel and also reinforcements 19 of tubular metallic material running in the same direction to brace the vertical tubular members 9 and also the transverse member 8 at the bottom.

It is stated and will be observed that all 70 the tubular members forming the frame of the vessel are filled with concrete, as shown at 20, and also at the bottom and sides of the hull, and the upper and lower decks extra reinforcements consisting of wire mesh are provided as particularly shown at 75 21. After the filling of the frame structure with cement or concrete a thin layer of concrete is placed along the inside of the structure as shown at 22. It will be understood 80 that the tubular members as shown and described will be made in sections and have 85 suitable joints for connecting the same.

Transverse members 8 and vertical members 9 have outer side openings 23 made in the tubing shown so that the concrete will 90 force through said perforations in the laying and form lugs to anchor the concrete that forms the shell of the vessel, supported by the frame as shown. In the construction I use slip joints 24 which I prefer to hold in 95 position by means of pins running through the same as shown in dotted lines wherein the openings therefor appear.

Although I have shown the preferred 100 form of my invention, and also described 110 the same, I claim all modifications that fall within its spirit and scope.

I claim:—

1. In a vessel a shell of concrete having a plurality of integral U-shaped ribs of tubing for the bottom and sides thereof provided with central openings and outer side openings, tubes extending longitudinally through said central openings, a filling of concrete in said ribs and continuously connected to said shell of concrete through said outer side openings, a central longitudinal concrete-filled tubular member through the bottom of said vessel having bent-up ends, transverse concrete-filled tubing for supporting the decks and extending into said U-shaped ribs, vertically and centrally placed hollow columns held by said tubular member and connected to said transverse concrete-filled tubing for supporting the same, a plurality of spaced vertical columns embedded in concrete endwise supported by said U-shaped ribs and the lowermost of said transverse concrete-filled tubing forming compartments for the bottom of said vessel, and slip joints for the sides of said ribs having apertures therethrough for pins.
- 15 2. In a vessel a shell of concrete having a plurality of integral U-shaped ribs of tubing for the bottom and sides thereof provided with central openings and outer side openings, tubes extending longitudinally through said central openings, a filling of concrete in said ribs and continuously connected to said shell of concrete through said U-shaped ribs, vertically and centrally placed hollow columns held by said tubular member and connected to said transverse concrete-filled tubing for supporting the same, and a plurality of spaced vertical columns embedded in concrete endwise supported by said U-shaped ribs and the lowermost of said transverse concrete-filled tubing forming compartments for the bottom portion of said vessel.
- 20 3. In a vessel a shell of concrete having a plurality of integral U-shaped ribs of tubing for the bottom and sides thereof provided with central openings and outer side openings, tubes extending longitudinally through said central openings, a filling of concrete in said ribs and continuously connected to said shell of concrete through said

outer side openings, a central longitudinal concrete-filled tubular member through the bottom of said vessel having bent-up ends, transverse concrete-filled tubing for supporting the decks and extending into said U-shaped ribs, vertically and centrally placed hollow columns held by said tubular member and connected to said transverse concrete-filled tubing for supporting the same, a plurality of spaced vertical columns embedded in concrete endwise supported by said U-shaped ribs and the lowermost of said transverse concrete-filled tubing forming compartments for the bottom of said vessel, and slip joints for the sides of said ribs having apertures therethrough for pins.

3. In a vessel a concrete shell, a plurality of integral U-shaped concrete-filled ribs of tubing in said shell provided with central openings and outer side openings, concrete-filled tubes running through said central openings and connecting said ribs, and concrete extending through said outer side openings and connecting the concrete filling of said ribs with the concrete shell.

In testimony whereof I affix my signature, in presence of two witnesses.

JOHN J. EAGAN.
